UNITED STATES PATENT OFFICE

CHAUNCEY L. BROWN, OF NORTHFIELD, MINNESOTA

OIL BURNER

Application filed July 18, 1929. Serial No. 379,224.

This invention relates to a liquid fuel burner more aptly designated simply as an oil burner applicable for use in various kinds of heating devices, particularly such as used for heating garages, small shops, and also highly efficient in water tanks such as used for stock watering purposes on farms.

The main object is to provide an oil burner of simple and inexpensive design and embodying certain features of construction and operation as hereinafter fully set forth, reference being had to the accompanying drawings in which,—

Fig. 1 is a top or plan view of the main burner member of my device alone and mounted on a horizontal heater element.

Fig. 2 is a diametrical sectional view as on line 2—2 in Fig. 1 and showing additional details and accessories of my device including fuel feed and overflow pipes, oil strainer, a cap over said strainer and a large upper deflector cap, the latter in dotted lines.

Fig. 3 is a partly sectional side elevation of my complete improved oil heater in operative position in a stove of the so-called garage heater type, said heater being designated in dotted lines only.

Fig. 4 is a top view of my oil strainer means.

Referring to the drawings by reference numerals, my heater device comprises an upwardly opening cup-like main shell 5 with an integral outwardly directed bolting or mounting flange 5A bored for bolts 6 by means of which the shell is fixed or mounted in a horizontal web 7W of a heater 7, said part 7W comprising the base, or false bottom or any other suitable horizontal element of the heater and having a bore through which the shell 5 is insertable upwardly to permit flange 5A to be attached. 5B is an interior concentric and integral, circular flange or cylindrical member extending upwardly from the bottom of shell 5 providing a circular oil burning trough 8 around it and between it and the outer shell wall. At the lower central part of shell 5, within cylinder 5B, the shell is cast or formed with an upwardly directed, approximately semi-spherical boss 5P, with a central vertical bore 9 tapped to re-

ceive a fuel intake pipe 10 from below, said bore 9 thus comprising a fuel passage through which oil flows upwardly and then flows down and outwardly radially on the rounded surface of boss 5P to the circular trough 11 formed between the base of said boss and the adjacent wall of cylinder 5B. 12 are a series of outwardly and downwardly inclined apertures in cylinder 5B near its upper edge and through which the liquid fuel flows outwardly from within the cylinder to the outer trough 8 where the fuel is burned.

13 is a metal cylinder-cap, preferably semi-spherical as shown and flanged at its opening, as 13F to rest concentrically on the upper rim of cylinder 5B, said cap being provided with an upper central ear 13E bored as 13B for readily handling same as with the end of a poker or other suitable rod, said cap being subject to intense heat when the burner is in use. 14 is a large main cap comprising mainly a plate with a number of radial downwardly directed, integral spacer webs 14W, each with a shoulder 14S so the cap may engage the rest concentrically on the upper rim of shell 5 (see Figs. 2 and 3) with the plate in vertically spaced relation to said rim. The plate serves as a deflector to spread the flames of the burning oil radially from and above the said rim of the shell, this feature being important particularly for heaters such as garage heaters (designated 7 in Fig. 3) to spread the heat to the walls of such heater and obtain maximum efficiency before the products of combustion are drawn toward and through the outlet flue 15 of such heater.

16 is an overflow cup or tray arranged concentric of and below shell 5 to receive any surplus fuel which may overflow from the trough 8 through a circular row of apertures 17 in the main shell 5. These apertures are bored or cored radial, upwardly and inwardly inclined preferably from a level just below flange 5A as shown and the main purpose of these inclined apertures is to provide means for directing a free, natural flow of air inwardly and upwardly to the fuel burning chamber or trough 8 and insure perfect combustion and maximum heat. It will be understood that the fuel passages 12 of the

center cylinders are preferably below the level of the apertures 17 of the main shell.

The cap 13 is used primarily as a means to cause preheating of the fuel, it being understood that fuel circulating outwardly from the inner cylinder will be heated within the cylinder by said cap as the outer surfaces of the latter is directly exposed to the flames of the burning oil within the upper part of shell 5. In fact it is obvious that when the heat is intense the fuel under cap 13 will boil and gasify or emanate from said chamber in semi-gaseous or entirely gaseous state in perfect condition for combustion in the burning chamber.

In Figs. 2 and 4 is illustrated a fuel cleaning or purifying device comprising three superposed inverted saucer shaped discs all of like diameter to be dropped down within the cylinder 5B to lie concentric therein and on top of the upwardly rounded boss 5P.

The bottom or lower disc of the three is designated 18 and comprises preferably a coarse mesh screen, the center one designated 19 is a disc of porous material such as asbestos or other heat resisting material and the top disc designated 20 is a perforated plate metal disc. All three of these superposed discs rest concentrically as described and over the fuel passage 9. Fuel flowing through said passage 9 fills the cylinder up to the outlet apertures 12 of cylinder 5B. Obviously the screen 18 not only supports the other discs but spreads the fuel and the latter passes through the porous center disc 19 and then upwardly through the apertured top disc. Thus foreign matter not desired in the burning chamber is separated by said discs and settles in the circular trough 11.

40 21 in Fig. 2 designates an overflow outlet pipe extending from the tray or catch basin 16 through which pipe surplus fuel is delivered to any suitable type of valve control means (not shown) well known in the art
45 and which regulates thereby the flow of fuel to the burner.

The use of my device has been fully disclosed but it will here be stated additionally that the inwardly and upwardly directed apertures 17 are important to provide natural and free flow of air to the fire chamber and complete combustion. The use and advantages of the cap 13 as described is another feature, providing preheating of fuel which is emitted in liquid, semi-gaseous or gaseous form to the fire chamber 8, another important condition contributing to the perfect combustion and all the above features resulting in maximum heating efficiency with little or no carbon formation.

I claim:

1. A liquid fuel burner comprising the combination of a cup-shaped main shell provided with exterior flanged mounting means 65 below its upper rim, the main body of said

cup comprising an upwardly opening cylindrical shell, an inner integral, cylindrical shell extending upwardly from the bottom of said cup to provide at the bottom a circular fuel burning trough, an upwardly projecting rounded boss integral of said bottom and concentric within the inner shell to provide a circular sediment trough between its base and the adjacent inner shell walls, said boss provided with a central fuel intake passage, fuel outlet means provided near the upper perimeter of said inner shell and air passage means provided in said outer shell at an elevation higher than said fuel passages of the inner shell. 80 70 75

2. The structure specified in claim 1 in which said apertures of the outer shell comprise a horizontal circular row of inwardly and upwardly inclined bores and said apertures of the inner shell comprising likewise inwardly and upwardly directed bores. 85

3. The structure specified in claim 1, and a removable fuel filtering element comprising three superposed plates adapted to lie normally concentric on said boss in the inner shell and over its fuel intake opening. 90

4. The structure specified in claim 1, and a removable fuel filtering element comprising three superposed plates adapted to lie normally concentric on said boss in the inner shell and over its fuel intake opening, said filtering element comprising a lower foraminous metal plate, an intermediate porous and liquid fuel filtering plate and an upper foraminous metal plate. 100

5. A liquid fuel burner comprising the combination of a cup-shaped main shell provided with exterior flanged mounting means below its upper rim, the main body of said cup comprising an upwardly opening cylindrical shell, an inner integral, cylindrical shell extending upwardly from the bottom of said cup to provide at the bottom a circular fuel burning trough, an upwardly projecting rounded boss integral of said bottom and concentric within the inner shell to provide a circular sediment trough between its base and the adjacent inner shell walls, said boss provided with a central fuel intake passage, fuel outlet means provided near the upper perimeter of said inner shell and air passage means provided in said outer shell at an elevation higher than said fuel passages of the inner shell, a removable upwardly rounded cap member formed with a circular lower flange arranged to fit and rest concentrically on the upper perimeter of the said inner shell, and a heat deflector cap member formed with a horizontal top plate and support means extending downwardly therefrom to support the said member with its top in horizontal plane in upper position.

6. A liquid fuel burner comprising a main upwardly opening cup shaped shell member 130

adapted to be mounted in a suitable heater, a central upwardly projecting boss on the bottom of said shell, an inner cylindrical shell concentric of said boss and opening upwardly with its upper perimeter in a plane lower than the upper perimeter of the main shell, said boss provided with a central fuel intake passage, fuel outlet means near the upper perimeter of said inner shell to deliver fuel freely outwardly radially and downwardly through said fuel outlet means into a combustion chamber formed between the inner and outer shells, and a removable semi-spherical cap adapted to rest concentrically on the rim of the inner shell with its outer surfaces exposed to the burning fuel, for the purpose of pre-heating the fuel within the inner shell.

20 In testimony whereof I affix my signature.
